UNITED STATES PATENT OFFICE.

FRANK M. SPAULDING, OF KALAMAZOO, MICHIGAN, ASSIGNOR OF ONE-HALF
TO FRANK C. BALCH, OF SAME PLACE.

RAILWAY-CROSSING GATE.

SPECIFICATION forming part of Letters Patent No. 446,082, dated February 10, 1891.

Application filed June 7, 1890. Serial No. 354,628. (No model.)

To all whom it may concern:

Be it known that I, FRANK M. SPAULDING, a citizen of the United States, residing at Kalamazoo, county of Kalamazoo, State of Michigan, have invented a new and useful 5 Railway-Crossing Gate, of which the following is a specification.

This invention relates to that class of railway-crossing gates which are operated through 10 certain mechanisms by the wheels of the train; and it has for its object the below described and claimed novel construction and combination of parts designed to facilitate the operation and insure greater safety to the operating 15 parts of the apparatus.

An important feature of the invention is to cushion the shock made by the sudden action of the cars, so that said shock will not be imparted to the gates and the chain or cable below 20 described, and thus obviate danger of breakage.

In the drawings forming a part of this specification, Figure 1 is a broken plan view. Fig. 2 is an elevation looking against the outside 25 of one of the rails of the track with parts broken away. Fig. 3 is an elevation of the front end of one of the gates. Fig. 4 shows broken details from Fig. 2, below described. Fig. 5 is a section on line 4 4 in Fig. 2, looking 30 from a point at the right. Fig. 6 shows enlarged lettered details from Fig. 5, parts being in section on line 4 4 in Fig. 2. Fig. 7 is an enlarged elevation of lettered details from Fig. 1, looking against the inside of one 35 of the rails of the track. Fig. 8 is a section on line 3 3 in Fig. 7, looking from a point at the right; and Fig. 9 is a plan view showing the gate transversely to the track, in which use it serves the purpose of a cattle-guard.

40 At a suitable distance from the point where a roadway crosses the track a long tread-bar is pivoted at one end at s to the inside of one of the rails of the track, Figs. 1, 2, and 7. This tread-bar rests upon a spring-support t, located between its two ends, and extends at an upward incline, so that a portion of said bar toward the free end extends above the upper surface of the rail.

45 In a bracket B, which is attached to the ties of the track, is journaled a rock-shaft F. This rock-shaft is provided with crank D at

its inner end, which is pivotally connected to an elongated slot in the free end of the tread-bar E at Z. The outer end of the rock-shaft is provided with a segmental gear G, which 55 meshes with the gear I', which gear I' is on the axle of the sheave H, and which axle has bearings in an upward extension of the bracket B, Figs. 1 and 2.

Between the gear I' and the sheave H is a 60 spiral spring N' on said axle, one end of which spring is attached to the gear I' and the other end to the sheave H, the same as the spring N in Fig. 6 is attached at the ends to the parts L M, and the sheave H is rigidly attached to its axle. By this means, when the tread-bar E is borne down by the wheels R of the cars (the train running from right to left in Fig. 1) the gear I' is turned on the axle of the sheave H until the tension of the spring 65 N' is such that the motion is imparted to the sheave H, at which time, of course, said sheave and its axle, the spring N', and the gear I' are all revolved together. By this means the first shock from the train is cushioned. The 70 sheave H bears a chain or cable w, which leads to the gate-operating mechanism in the case A and is attached to the sheave L thereof. Since the shock of the train is cushioned by the spring N', there is no undue strain 75 brought to bear upon the chain or cable w, and hence danger of breaking the same is obviated. If preferred, this chain or cable may be provided with the ordinary spring-sections y to still further guard against an 80 undue strain upon the chain or cable w.

The gate C, which consists of the two trussed bars, one each side of the upper end of the case A, converging toward their outer end, as in Fig. 9, and provided at the rear end 90 with weights a a of the ordinary construction, is attached to the axle of the gear-wheel K, which has bearings in said case. Below the axle J is a shaft f, upon which is loosely mounted the sheave L at one end of said shaft. 95 At the other end is the gear M, rigidly attached to said shaft by the set-screw X.

Upon the shaft f and between the sheave L and gear M is a spiral spring N. The ends of this spring are attached to the gear M and sheave L at v v, Fig. 6. The gear M of the shaft f meshes with the gear K of the axle J.

The function of this spring is the same as that of the spring N', hereinbefore described—that is, it cushions any shock which is not sufficiently cushioned by the spring N', thus insuring greater safety to the mechanism and preventing a sudden downward throw of the gate to its horizontal position across the roadway, it being understood, of course, that when the chain w winds upon the sheave H it turns the sheave L, because the chain w is attached thereto, and when the spring N is sufficiently compressed or wound as tightly as it can be on the shaft the motion is then imparted to the gear M and the shaft f, and all these parts L, M, N, and f revolve.

The spring N performs still another function, viz: After the train has cleared the bar E and the gate is raised to a vertical position by the weights a a, the spring N yields in conformity to the swaying motion of said gate in the wind, thus preventing an undue strain upon the mechanism and obviating danger of breakage and straining of parts. The chain w, which is attached to the sheave H, passes between the pulleys e at the lower right-hand corner of the case A and passes from thence upward and is attached, as before stated, to the sheave L.

Referring to Fig. 1, a chain or cable u is attached to the chain w, passes around pulley O, and from thence crosses the track and passes around a pulley 2 to mechanism within the case A', which is a duplicate of that heretofore described within the other case A, and from which the chain w' leads out in the opposite direction to other track mechanism which is operated by the wheels of the train coming from the other direction, said other mechanism not being here shown, but being like that shown in Figs. 1 and 2. Of course the object of this is that the train coming from either direction may lower both gates, one at each side of the track at a road crossing, or that when the modification is employed as a cattle-guard the gate C may be lowered each side of a roadway which crosses the track and transversely to said track, one of said gates being shown in said Fig. 9.

Returning to Fig. 1, a chain or cable u' is attached to the chain w', from thence passes around pulley 3, and leads across the track and around pulley z, on between pulleys 5 at the lower left-hand corner of the case A, and upward to the sheave L, to which it is attached. By this means when the train is coming from the right hand the chains w and u will be tightened, and hence turn their respective sheaves and lower the gates C, and during this action the chains w' and u' will be slackened, as indicated by the chain u' in Fig. 2. Of course when the train is coming from the opposite direction the chains w' and u' will be tightened and the other chains w and u slackened.

Referring to Fig. 3, h is a signal-flag mounted upon a staff g, which is pivoted at i to the side of the gate C at a point above the lon-

gitudinal center of said staff, so that when the gate is raised the staff g will swing to a vertical position parallel with the sides of 70 said gate. The staff g is provided at the lower end with a rubber cushion or spring l to relieve the shock in case the gate swings down too suddenly to its horizontal position, it being understood, of course, that during 75 said action the signal-staff swings to a vertical position, as shown in Fig. 3, its lower end coming in contact with the ground. The object of this signal h is the same as heretofore— 80 to attract people's attention.

The case A is provided with laterally-projecting stops b, Figs. 1 and 2, said stops being provided with a rubber or spring cushion 6 on the under side. The object of these stops is to prevent the gate from swinging 85 lower than to a horizontal position, which of course is accomplished by the upper side of the bars of the gate in the rear of their fulcrum coming in contact with said stops.

In Fig. 2 is shown a bell at P, mounted upon the case A, the clapper-lever m of which is provided with a pivoted dog n in a position for a projection r on the sheave L to come in contact with said dog, and thus operate the bell just before the gate starts to swing down 90 to give warning to pedestrians, so that they will not be caught by the downward-swinging gates. The lever m is provided with a projection o, against which the end of the dog n comes in contact when the sheave L is 100 turned in a direction to lower the gates, as indicated by the arrow in Fig. 4. The object of thus pivoting the dog n so as to come in contact with the projection o of the lever m is that the bell will be operated when the sheave 105 is turned in the direction just described, and so that said dog will tilt to the dotted position in Fig. 4, and thus be kept free from the projection r of the sheave when the latter turns in the opposite direction. The free end 110 of the tread-bar E is turned away from the rail, as in Fig. 1, so that when the train is running in a direction to approach this end first the flange of the wheels will run between the bar E and the rail of the track, and thereby crowd the bar E away from the rail of the track, so that it will not be pressed down by the train going in said direction. This is of course to prevent the gate from being swung down after the train has crossed the crossing. 115 When the wheels crowd the bar E away from the rail, the rock-shaft F is moved endwise in its bearings by said bar E, and the spring e on the end of the rock-shaft and against the side of the bracket B carries the parts F 120 and E back to place after the train has passed. 125

Having thus described my invention, what I claim as new, and desire to secure by Letters Patent of the United States, is—

1. The combination of a rail of the track, 130 a tread-bar pivoted at one end to said rail, a rock-shaft having a crank pivotally attached to said bar, a sheave, a chain or cable attached at one end to said sheave, an axle upon

which said sheave is loosely mounted, gear-connections between the axle and the rock-shaft, a second shaft bearing a cushioning-spring, a sheave loose upon said shaft, the other end of the chain being attached to said sheave, an axle above the second shaft, the gate attached to said axle, and gear-connections between the second shaft and axle, substantially as set forth.

5 2. The combination of a rail of the track, a tread-bar pivoted at one end to said rail, a rock-shaft having a crank pivotally attached to said bar, a sheave, a chain or cable attached at one end to said sheave, an axle upon which 10 said sheave is loosely mounted, a cushioning-spring upon said axle, gear-connections between the axle and the rock-shaft, a second shaft bearing a cushioning-spring, a sheave loose upon said shaft, the other end of the 15 chain being attached to said sheave, an axle above the second shaft, the gate attached to said axle, and gear-connections between the second shaft and axle, substantially as set forth.

20 3. The combination of a rail of the track, a tread-bar pivoted at one end to said rail, a rock-shaft having a crank pivotally attached to said bar, a sheave, a chain or cable attached at one end to said sheave, an axle upon which 25 said sheave is loosely mounted, a cushioning-spring upon said axle, gear-connections between the axle and the rock-shaft, a second shaft bearing a cushioning-spring, a sheave loose upon said shaft, the other end of the 30 chain being attached to said sheave, an axle above the second shaft, the gate attached to said axle, gear-connections between the second shaft and axle, a case housing the 35 latter-named shaft, axle, and their connections, 40 and in which case said shaft and axle have

bearings, the bell mounted upon said case and provided with the pivoted clapper-lever, the projections on said lever and sheave, and the dog pivoted to said lever, substantially as set forth.

45

4. In a railway-crossing gate, the combination of a spring-supported tread-bar adapted to be borne down by the wheels of the train, a shaft, a sheave loosely mounted thereon, a gear rigidly attached thereto, a cushioning-spring between them attached at the ends to 50 said sheave and gear, said tread-bar being operatively connected with the axle of the sheave, a gate adapted to swing up and down across a street or track, a sheave operatively connected with 55 said gate by suitable mechanisms, and a chain or cable attached at the ends to the sheave, substantially as set forth.

5. In a railway-crossing gate, the combination of a spring-supported tread-bar adapted to be borne down by the wheels of the train, a shaft, a sheave loosely mounted thereon, a gear rigidly attached thereto, a cushioning-spring between them attached at its ends to 60 said sheave and gear, said tread-bar being operatively connected by means of a rock-shaft provided with a crank and segmental gear with the axle of the sheave, a gate adapted to swing up and down across a street or track, a sheave operatively connected with 65 said gate by suitable mechanisms, and a chain or cable attached at its ends to the sheave, substantially as set forth.

In testimony of the foregoing I have hereunto subscribed my name in presence of two 70 witnesses.

FRANK M. SPAULDING.
